(57) **CLAIM**

The ornamental design for a cable display mount as shown and described.

DESCRIPTION

FIG. 1 is a perspective view of a cable display mount showing my new design;

FIG. 2 is a front elevation view thereof;

FIG. 3 is a rear elevation view thereof;

FIG. 4 is right side elevation view thereof;

FIG. 5 is a left side elevation view thereof;

FIG. 6 is a top plan view thereof;

FIG. 7 is a bottom plan view thereof;

FIG. 8 is a second perspective view thereof; and,

FIG. 9 is another perspective view thereof, shown in an environment of use.

The broken lines shown in FIGS. 1-3, 6 and 8 illustrate portions of the cable display mount that form no part of the claimed design. The broken lines illustrating the monitor and assembly parts in FIG. 9 are environment, while the remaining broken lines in FIG. 9 illustrate portions of the cable display mount that form no part of the claimed design.

1 Claim, 7 Drawing Sheets
